UNITED STATES PATENT OFFICE.

FRANK L. DYER, OF MONTCLAIR, NEW JERSEY.

ART OF RECORDING AND REPRODUCING SOUNDS.

Application filed May 7, 1923. Serial No. 837,198.

To all whom it may concern:

Be it known that I, FRANK L. DYER, a citizen of the United States, residing at Montclair, in the county of Essex and State 5 of New Jersey, and having a post-office address at No. 115 Broadway, New York city, have invented certain new and useful Improvements in the Art of Recording and Re-producing Sounds, of which the following is 10 a full, clear, and exact specification.

My invention relates to improvements in the art of recording and reproducing sounds. As now made, talking machine records permit the recording of sounds over a very 15 limited period of time, generally in the neighborhood of three minutes, more or less; as a result any music recorded thereon is necessarily abridged and mutilated, and so-called talking records are limited in subject 20 matter.

The limitation as to time in existing talking machine records is made necessary by the conditions of the art as now practiced. It being an essential that the sounds which are 25 to be directly reproduced from the record shall be loud enough to fill a large sized room, it has been found necessary to make use of a relatively ponderous sound-box carrying a relatively large diaphragm, the 30 whole resting upon a pointed needle which tracks the record and which engages the record with a pressure of many thousand pounds per square inch. To prevent such a needle from cutting and destroying the 35 record material with which it engages, it is necessary that the record material should be moved with respect to the needle at a relatively high speed, and experience has shown that a mean surface speed in the neighbor-hood of 40 inches per second is desirable in 40 practice. It has been found that at this surface speed of the material a sound-box of sufficient weight to give the necessary sounds can be supported by a needle with com- 45 mercial results as to wear, provided the record groove is of sufficient width to give a relatively extended bearing surface for the needle when the point of the latter has worn down sufficiently to fill a substantial portion 50 of the record groove, and therefore it is the present practice to make these record grooves substantially .005 inch in width and with a depth ranging from .002 to .003 inch.

The amplitude of the sounds reproduced 55 from the record depends upon the extent to which the groove may vary on either side

of its medial line or in other words upon the amplitude of the lateral or vertical undulations of the record groove, and I have observed from a study of many records that the maximum sounds recorded represent a vibration of between .001 and .002 of an inch. To permit the recording of sounds represented by an amplitude of this order or possibly greater, and at the same time provide sufficient material between adjacent grooves to properly actuate the needle and prevent it from short-circuiting, it has been necessary in practice to employ a feed of the order of .01 inch, whereby the lands 60 between the grooves will be of a mean width of .005 inch corresponding with that of the record groove. These limitations as to width of groove, width of lands, and surface speed make it impossible with a record disk 65 of a diameter of 10 or 12 inches or thereabouts, or a corresponding cylinder, to secure a sound record of much more than 3 minutes in length, with corresponding restriction as to character and subject matter. 70

What I propose by my present improvements, is to very greatly extend the capacity of a record of the present standard size by obtaining thereon a record of sounds of an hour or more representing an extension of 75 25 fold as to time. In this way it will become possible to record very long musical compositions or to record several long musical compositions on one face of a record; it will become possible to make a record of 80 stories of considerable length; it will become possible on two or three double faced records to record an entire novel, since three records would represent six hours of solid reading; and it will become possible to record upon a 85 record disk of very small size a much longer selection than can possibly be recorded and satisfactorily reproduced under existing conditions on records of standard size. My improved record will be especially acceptable 90 to the blind, to whom reading by existing methods is tedious and unsatisfactory.

What I propose, in brief, is to make a record groove of microscopic size, preferably of the order of .001 inch in width, or 100 at least substantially and materially narrower than any talking machine record of which I have knowledge. The depth of the groove is not important, so long as it shall be in reasonable proportion to the width. I 110 have frequently cut record grooves of the order of a thousandth of an inch in width

and have found that the ordinary recording material is sufficiently uniform and amorphous to permit such a groove to be cut with great smoothness and sharpness.

5 In cutting a record groove of the width indicated, I make use of a proportionate surface speed or approximately so; that is to say, if the width of the groove is reduced five-fold to .001 inch, the surface speed is 10 preferably reduced in proportion, to preferably a shaft speed of about 16 turns per minute or a mean surface speed of the order of eight inches per second.

15 The sounds which I record in such a groove of extreme narrowness and formed at low speed are so controlled or adjusted that the recorded amplitude thereof will bear substantially the same ratio to the surface speed as with existing practice; that 20 is to say, if the maximum amplitude of sounds as recorded on present records is of the order of .001 inch, then with my improved record the recorded amplitude will be approximately .0002 inch. This control 25 of the sounds to be recorded may be effected in many ways, as by using original sounds of small volume, or by using a recording diaphragm of relatively great thickness to limit the amplitude of its response, or by 30 using a recording diaphragm of small diameter so as to have a limited response, or by adjusting the leverage of the needle arm of the recording device whereby the movement of the cutting stylus will be properly limited.

35 It will be seen that the proposed record will have substantially the same relations as to width, surface speed and amplitude as existing records. With such a record it becomes possible to make a proportionate reduction in the pitch of the record groove; 40 with the example under consideration the pitch will be reduced from .01 inch to .002 inch.

45 By cutting down the pitch of groove five-fold and by reducing the surface speed five-fold, I increase the time represented by the record groove twenty-five fold or, say, from three minutes to seventy-five minutes, while 50 at the same time the record groove has sounds recorded thereon in proper relation to the surface speed as well as to the width of groove and width of lands between the grooves. The sounds recorded in the groove differ only from the sounds in the grooves 55 of existing records in the respect that they are of less amplitude, but otherwise they are perfectly and accurately formed. Being recorded at low speed and involving the removal of a minute amount of material 60 the recorded sounds are relatively free of distortions noticed in existing records which are due to removal of relatively large amounts of material at relatively high speeds.

65 Such a record as I have above proposed,

could not be used effectively for direct reproduction; a sound box for that purpose would have to be too heavy and direct reproduction under any circumstance would be weak, owing to the limited amplitude 70 of the recorded sounds. I, therefore, propose to use a reproducing device bearing upon the record with a pressure proportional to the width and length of the groove, say with a pressure of from one-quarter 75 to one-half an ounce, and by suitable amplifying means I increase the volume of the sounds to the desired extent. It is possible to use exterior amplifying means to 80 enlarge the comparatively feeble sounds on the record to any desired extent; to as loud or louder than existing records with direct reproduction, while at the same time the wear on the improved record is no greater than with present records. The sounds from 85 my improved record may be amplified in any suitable way, for instance, for reading, ordinary listening tubes or a simple telephone may be employed, while if loud effects are wanted, the feeble sounds on the record may 90 be amplified by an ordinary loud-speaker of the radio type or some such device having as many stages of amplification as may be desired. Devices of this kind are capable 95 of producing enormous amplification with but relatively little distortion. If listening tubes or a stethoscope is used as an amplifying device, it will be understood that the reproducing device will be equipped with 100 a small light diaphragm actuated directly 100 from the record, but if the amplifying device is electrical, as is preferred, then the needle tracking the record groove will actuate a suitable microphone, the varying currents of which will either actuate a telephone receiver directly or be amplified before reception by any suitable arrangement of thermionic valves or other amplifiers.

105 In order that the invention may be better understood, attention is directed to the accompanying drawings forming part of this specification, and in which:

Fig. 1, is a cross sectional view of a record of the ordinary type and dimensions, illustrating three of the grooves, with the lower end of a needle engaging the center groove;

Fig. 2, a corresponding cross section through my improved record, on the same scale, with a needle engaging one of the 115 grooves;

Fig. 3, a plan view of the standard record shown in Fig. 1;

Fig. 4, a similar view of the improved record;

Fig. 5, a plan view of a portion of an apparatus for reproducing from my improved record, employing a microphone as a transmitting device;

Fig. 6, a side elevation of Fig. 5, partly 130

in section, looking in the direction of the arrow 6;

Fig. 7, a section on the line 7—7 of Fig. 6;

Fig. 8, a cross sectional view, on a larger scale, showing the details of a suitable microphone arrangement;

Fig. 9, a section at right angles to Fig. 8, looking in the direction of the arrow 9;

Fig. 10, an elevation partly broken away showing a suitable arrangement of carrying case for the apparatus for reproducing from my improved record; and

Fig. 11, a suitable circuit, in diagram, showing one stage of amplification for use with reproducing apparatus herein referred to.

In all of the above views corresponding parts are represented by the same reference characters.

20 Referring first to Figs. 1 and 3, 1 represents a small portion of an ordinary record having a record groove 2 therein; ordinarily this record groove is about .005 inch in width, about .002 in depth, and with a pitch 25 of .01 inch or one hundred threads to the inch. In Fig. 3, the groove is shown as having a deflection, representing sound, of .001 inch, this being the order of amplitude of maximum sounds recorded on talking machine records. It will be understood that the record is a duplicate copy obtained in the usual way from a suitable master cut in an amorphous and uniform material in the usual 30 way.

35 Referring now to Figs. 2 and 4, the record groove 3, shown therein is illustrated as being one-fifth the width of the ordinary groove and one-fifth the relative length thereof; that is to say the groove is .001 inch 40 in width and the surface speed at which it is formed is approximately eight inches per second, average; its depth is substantially proportional to the standard record shown in Figs. 1 and 3. With these proportions 45 the record, as shown in Fig. 4 has one twenty-fifth the area of the standard record and hence the time of reproduction is increased twenty-five fold. It is of course not necessary that these dimensions shall be precisely 50 followed; by reducing the width of the groove and proportionately reducing the surface speed the time of reproduction is increased in proportion to the product of the two factors; a record of one-third the 55 usual width and one-third the speed will represent a nine-fold increase in time, and so on. It is important that there should be a substantial reduction in the width and surface speed as compared with present 60 practice, since the opportunity of exterior amplification is practically unlimited and the important consideration is to increase the time of reproduction at least several fold so as to thereby extend the talking machine into fields that are now unthought of.

It will be observed that the amplitude of the recorded sound in Fig. 4 is proportional to that of Fig. 2, so far as width and length are concerned. In other words, the maximum amplitude with a record groove 70 of .001 inch should be of the order of .0002 inch. As I have indicated a sound groove of this sort can be obtained in various ways, but of the expedients suggested I prefer to secure the desired limited range of amplitude by using an ordinary recording apparatus operated in the usual way, but I so adjust the leverage of the arm or lever which carries the cutting tool that the deviation of the cutting tool will be properly reduced in extent; in the assumed case, the leverage will be such that the cutting tool will be vibrated only one-fifth as far on either side of the medial line as with present practice.

75 As indicated, the feed or pitch of the record groove is reduced in proportion to the width, that is to say when the width of the groove is reduced to .001 inch, the pitch of the groove will be reduced to .002 inch or five hundred threads to the inch.

80 The needle 4 which tracks the groove of my improved record is properly proportioned to the size of the groove and has practically the same relation thereto as the ordinary needle 5 tracking the regular sized groove 2; in use the relatively pointed end will quickly wear down to increase the bearing surface and fill the groove more or less; it is important that the extremity of the needle shall have the right proportion; the shank may be relatively large so as to give 85 rigidity and permit the needle to be handled more easily. I find that the ordinary recording material is so uniform and amorphous that a sound groove of .001 inch in width may be cut therein with beautiful sharpness and clearness; moreover the methods now used of making duplicate copies from master records are so very perfect that even when the record has been reduced in width five fold as contemplated herein the copies obtained from such a master will be 90 practically perfect and free from foreign sounds.

100 95 In securing reproduction from such a record as I have above described, I take advantage of exterior amplifying devices and I prefer to have the record actuate a microphone rather than a diaphragm as when the amplification is secured by the use of a stethoscope. I will therefore describe electrical amplification although it will be understood that the reproducer needle may 105 actuate a small and sensitive diaphragm 110 the feeble vibrations of which may be detected by the use of listening tubes.

115 120 My improved record, shown in Fig. 6, at 6, is carried on a turn-table 7, driven in any suitable way, as by an electric-motor, 125 illustrated conventionally at 8, in Fig. 10.

It is turned at a speed equal to that at which the master was made; in the assumed case of a record groove of .001 inch in a 10 or 12 inch disk the shaft speed will be preferably about sixteen turns per minute.

- The needle 4 is carried in a suitable holder 9 at the end of a lever 10, mounted to vibrate on pivots 11, 11, with as little friction as possible and with no lost motion. 10 The pivots are mounted in a suitable casing 12, within which is the lever 10, and said casing is provided with integral extensions 13, 13, giving room for a tension wire 14, to which the upper end of the lever 16 is connected. Said tension wire offers an elastic support for the upper end of the lever or needle-arm and permits the latter to vibrate like a reed; at the same time the wire is practically aperiodic or at least its fundamental is so high as to be without effect. 20 The tension wire may be adjusted by the regulating screw 14.

- At one side of the casing 12, is an extension 15, in which is located the microphone. 25 Any desired arrangement of microphone may be used; I show a well known form comprising the carbon granules 16, and the two contact buttons 17, 17, one of which connects with the needle arm and the other of which is adapted to be adjusted by a screw 18.

- The microphone-reproducer described is carried at the extremity of an arm or tube 19, which may be an integral extension of 30 the casing 12. This arm is mounted on horizontal pivots 20, 20, in a ring 21, and the latter is mounted on a vertical pivot 22, as shown particularly in Fig. 7, whereby the arm 19 may be free to swing laterally as the 35 needle tracks the groove and also it may be lifted off of the record when desired. It will be seen that the construction described is very light as it is important that the pressure of the needle on the record shall be only a fraction of an ounce. In order that 40 the parts may not be fragile and at the same time to secure the desired lightness of pressure, I preferably employ an adjustable counteracting spring 23, arranged between 45 the arm 19 and an arm 24, projecting from the ring 21, whereby the counteracting spring will be unchanged in its relation to the arm 19.

- Preferably the ring 21, is provided with a 50 pointer or indicator which cooperates with a suitable scale 26, to facilitate engaging the needle with the record at any desired point thereon.

- The microphone may be connected in any 55 desired circuit for the purpose; it may be arranged in a simple circuit with a battery and a telephone receiver or head-set. Or it may be connected in circuit with a loud-speaking device, such as are used for radio 60 reception, with as many amplifiers as may be

desired; for instance, in Fig. 11, I show the microphone contacts in a circuit 27, which is coupled to an amplifying circuit 28, the output side of which is coupled to a circuit 29 including the loud-speaker or other receiver. 70

Mechanism for commercially utilizing my improved talking machine records is simple and it can be made very compact, not only because of the inherent smallness of the 75 elements thereof but particularly because it is not necessary to use a bulky horn and tone-arm. Therefore, the entire device can be mounted in a compact carrying case as shown in Fig. 10, having a cover 30 80 which may be opened up to disclose the turn-table and reproducing mechanism, and also provided with a hinged front 31, which may be let down to disclose the motor 8 and batteries 32 for the telephone current. It is intended, if an electric motor is used that it will be operated from a suitable storage 85 battery or from the usual light circuit.

While I have specifically described my improved talking machine record as having a groove of the laterally undulatory type, it will be understood that the invention may be carried out with records having hill and dale grooves, it being only necessary to properly proportion the width, length and amplitude as herein described. If the hill and dale groove is adopted, I prefer to form the same with a wedge shape cutter, giving substantially the cross-section of Fig. 3. 90 With such a groove, a needle may be used for reproduction, and will track the groove with facility and certainty. A groove of this kind is preferred to one formed with a curved edge cutter and in which the groove is extremely shallow and relatively wide, 95 since with such a groove a rounded reproducing stylus is used, generally a sapphire or diamond, and difficulty would be experienced in tracking the groove if reduced to the microscopic dimensions contemplated by 100 my invention. 105

Having now described my invention, what I claim as new therein and desire to secure by Letters Patent, is:

1. In the art of reproducing sounds, a 115 talking machine record having a sound groove materially less than .005 inch in width, representing sounds recorded at a surface speed materially less than forty inches per second, a reproducing device having a needle engaging the record with a pressure of less than one ounce and means for securing an amplified response from said needle substantially as set forth.

2. In the art of reproducing sounds, a 125 talking machine record having a sound groove approximately .001 inch in width, representing sounds recorded at a surface speed of approximately eight inches per second, a reproducing device having a needle 130

engaging the record with a pressure of less than one ounce and means for securing an amplified response from said needle substantially as set forth.

5. In the art of reproducing sounds, a talking machine record having a record groove approximately .001 inch in width, representing sounds of a maximum amplitude of approximately .0002 inch recorded at 10 a surface speed of approximately eight inches per second, a reproducing device having a needle engaging the record with a pressure less than one ounce and means for securing an amplified response from said needle 15 substantially as set forth.

4. In the art of reproducing sounds, a talking machine record having a microscopic groove in width, length and amplitude as compared with existing practice, the values 20 of width and length being so chosen as to permit the recording on a ten inch disc of sounds extending over a period of ten minutes or more, a needle engaging the record groove with a pressure sufficiently light 25 as not to result in substantially greater wear than with existing practice, and means for securing an amplified response from said needle, substantially as set forth.

5. In the art of reproducing sounds, a 30 talking machine record having a microscopic groove in width, length and amplitude as compared with existing practice, the values of width and length being so chosen as to permit the recording on a ten inch disc of 35 sounds extending over a period of ten minutes or more, a needle engaging the record groove with a pressure sufficiently light as not to result in substantially greater wear than with existing practice, a telephone 40 transmitter actuated by the needle, and a magnetic receiver actuated by the telephone current, substantially as set forth.

6. In the art of reproducing sounds, a talking machine record having a microscopic groove in width, length and amplitude as compared with existing practice, the values 45 of width and length being so chosen as to permit the recording on a ten inch disc of sounds extending over a period of ten minutes or more, a needle engaging the record groove with a pressure sufficiently light as not to result in substantially greater wear than with existing practice, a telephone transmitter actuated by the needle, a thermionic amplifier for amplifying the telephone current, and a magnetic receiver actuated by the amplified current, substantially as set forth.

7. In the art of reproducing sounds, a 50 talking machine record having a groove approximately .001 in width and representing sounds recorded at a surface speed of approximately eight inches per second, a needle engaging the record groove with a very

light pressure, a telephone transmitter actuated by the needle, a thermionic amplifier for amplifying the telephone currents and a magnetic receiver actuated by the amplified currents substantially as set forth. 65

8. In the art of reproducing sounds, a 70 sound record groove of microscopic width representing sounds of feeble amplitude recorded at a low surface speed, the values of width and surface speed being so chosen as to permit sounds extending over a period 75 of ten minutes or more to be recorded on a ten inch disc, a telephone transmitter actuated by the record groove, a thermionic amplifier for amplifying the feeble telephone currents, and a radio loud speaker actuated by the amplified currents, substantially as 80 set forth.

9. In the art of reproducing sounds, a 85 sound record groove substantially less than .005 in width representing sounds recorded at a surface speed substantially less than forty inches per second and of such feeble amplitude as to be incapable of direct mechanical reproduction through a horn, a telephone transmitter actuated by the record groove, a thermionic amplifier for amplifying the feeble telephone currents, and a radio loud speaker actuated by the amplified currents, substantially as 90 set forth.

10. In the art of reproducing sounds, a 95 sound record groove substantially less than .005 in width representing sounds recorded at a surface speed substantially less than forty inches per second and of such feeble amplitude as to be incapable of direct mechanical reproduction through a horn, and means for securing an amplified response from said record, substantially as set forth. 100

11. In the art of reproducing sounds, a 105 talking machine record having a sound groove therein, a needle engaging the record groove with a pressure of less than one ounce, means for converting the vibrations of the needle into feeble telephone currents, thermionic means for amplifying said currents, and a magnetic receiver actuated by the amplified currents, substantially as set forth. 110

12. In the art of reproducing sounds, a 115 talking machine record having a sound groove therein representing sounds too faint for direct mechanical reproduction through a horn, a needle engaging the record groove with a pressure of less than one ounce, means for converting the vibrations of the needle into feeble telephone currents, thermionic means for amplifying said currents, and a magnetic receiver actuated by the amplified currents, substantially as set forth. 120

This specification signed this fifth day of May, 1923. 125

FRANK L. DYER.
